UNITED STATES PATENT OFFICE.

JOHN C. SILLIMAN, OF PALO ALTO, CALIFORNIA.

VEIN STABILIZER.

Application filed April 1, 1925. Serial No. 19,926.

To all whom it may concern:

Be it known that I, JOHN C. SILLIMAN, a citizen of the United States, and residing at Palo Alto, Santa Clara County, State 5 of California, have invented certain new and useful Improvements in Vein Stabilizers, of which the following is a specification.

This invention relates to vein stabilizers 10 or instruments for the purpose of facilitating the holding of a vein for the insertion of an intravenous needle for the purpose of making blood tests or injections into the veins.

15 It is the general object of the present invention to provide a novel vein stabilizer which will securely and firmly hold and position a vein for the insertion of a needle.

Another object of the present invention 20 consists in the provision of a simple and convenient vein stabilizer adapted to hold and firmly position a vein and allow a portion of it to protrude for the easy insertion of an intravenous needle.

25 In the practice of surgery and medicine it often becomes necessary to insert into a vein a hollow needle either for the purpose of withdrawing blood from the vein or for injecting into it any of the various fluids. 30 or solutions used in medicine or surgery. Up until the time of the present invention it has been the usual practice, as evidenced by numerous medical text books, for the doctor to endeavor to hold the vein which 35 is to be punctured between two fingers or between a thumb and a finger in order that it may remain stationary so that a needle can be easily inserted into it. However this procedure is not at all simple and as a re-

40 sult a number of false efforts are made to insert the needle into the vein properly, often with painful results to the patient. The present invention provides a simple device for properly holding or stabilizing the vein 45 and causing it to project through a slot so that the needle can be properly inserted with ease and facility. It is necessary that the needle be inserted longitudinally of the vein otherwise there is a possibility of it

50 going through the vein and coming out on the other side so that its hollow end will not be effective to insert a solution in or extract blood from the vein.

In the accompanying drawings and following specification there is disclosed by

way of example only, two embodiments of the present invention with the understanding however that various changes may be made in the shape, size, arrangement, proportion and material of the various parts 60 without departing from the spirit of the invention as set forth in the appended claims.

In said drawings:

Fig. 1 is an elevation of the instrument 65 in use and shown in position on the arm of a patient;

Fig. 2 is a perspective view of the instrument; and

Fig. 3 is a similar view of a modified 70 form.

Referring to the drawing there is disclosed generally at 10 the vein stabilizer preferably formed of sheet metal such as 75 aluminum, brass or steel, suitably nickel plated, if preferred. The thickness of the metal is about one-sixteenth of an inch. The instrument comprises two portions, the handle 11 and the blade 12 which is bent 80 away from the axis of the handle at an angle of substantially 30°, along the line 13, at right angles to the axis 14 of the handle. The overall length of the instrument is about 7½ inches. The width of the handle is about 1 inch at its widest part 85 and the width of the blade about 1½ inches. The side 15 of the blade is substantially parallel to the axis of the instrument and almost straight, whereas the side 16 widens out from the line 13 and is arcuate in form 90 and the end 17 of the blade is clipped at substantially an angle of 120° to the side 15, as best shown in Figure 1.

The clipped end of the blade is provided 95 with a notch or slot 18 extending clear through the blade and substantially ¾ of an inch deep and ⅜ of an inch wide and having its long axis at right angles to the clipped end 17 or an angle of about 30° to the axis of the blade. Both the blade 100 and the handle are substantially oval in shape and the instrument may be described as a flat, solid spatula with rounded edges and a smooth finish.

As shown in Figure 3, the instrument 105 may be formed of wire instead of sheet metal in which case a sufficiently strong and rigid wire 19 will be bent into the form of the outline of the instrument.

In use the device is applied as shown in 110

Figure 1. The patient is preferably seated or placed in a reclining position and the arm, if a vein is to be punctured there, is bared well above the elbow. A rubber tube or band 20, the usual rubber band used in this work, or any constrictor in fact, is wrapped about the upper arm midway between the elbow and the shoulder until venous circulation is cut off. The veins now 10 swell up to a certain degree and in order to make them swell more, the patient is caused to open and close the hands 6 or 8 times, then hold the fist tightly closed. This pumps more arterial blood into the arm and the clinching still further drives the blood into the surface veins. Every vein should 15 now stand out prominently and the operator selects one of the most prominent and faces the patient with the stabilizer in the left hand and the intravenous needle in the right hand, as shown in the figure. The stabilizer is pressed with the blade flat on the arm and the notch exactly over the vein to be entered which will cause the vein to bulge up 20 through the notch 18, covered by the skin of course and to remain held absolutely still and immobile as if it were made of putty. This takes place because the blood in the vein is cut off above by the constrictor and 25 below the point in which it is desired to make an entry by the flat portion or blade of the stabilizer at the base of the notch which presses down upon the skin and closes the vein. Therefore the blood can not move 30 and neither can the vein move but everything is held steady. The needle is next brought up and slid over the base of the notch in the blade of the stabilizer with the right hand and can thus easily be introduced 35 into the vein and longitudinally thereof as shown. The test of getting the needle into the vein and not through it or beside it, lies in the fact that blood will be seen to enter the glass of syringe if the proper entry is 40 made or if a needle alone is used, for a blood test, blood will flow freely from the needle. At this time the constricting band should be 45 loosened and the stabilizer blade slipped out from under the needle.

50 The arrangement and proportion of the various parts of the instrument is of extreme importance. For instance, the angle of the notch in the end of the stabilizer is so arranged that the axis of the vein being operated on points to the right hand and right shoulder of the operator in which hand the needle is used. This facilitates the entry of the needle along the axis of the vein. The thickness of the instrument is of extreme 55 importance as the vein must bulge up through the notch to allow the needle to guide over the base or blade of the stabilizer and into the bore of the vein. The angle of 30° between the blade and the axis of the handle is of importance since it is essential 60

that the blade must be flat on the arm or leg while the handle is in a position to be grasped by the left hand of the operator. It has been found that the width of the notch 70 is of considerable importance for if a wider notch is used, the vein is inclined to slip, whereas with a narrower notch many veins are too large to bulge up into it properly. The depth of the notch is quite important in that its walls extend sufficiently along the 75 walls of the vein to allow a proper insertion of the needle. A large number of experiments extending over quite a period of time have been necessary to finally bring the instrument to its present perfected form. It 80 will be readily apparent to all those skilled in the art that by the use of this instrument the operation can be performed with much more facility and ease than by the makeshift means of attempting to hold the vein with 85 two fingers.

Having thus described the invention what is claimed as new and desired to be secured by Letters Patent is:

1. A venous stabilizer for use in vein 90 puncture, including a handle and a substantially flat blade portion having a notch therein, said blade portion being adapted to be pressed over a distended vein to close one end thereof with the vein projecting 95 through said notch.

2. A venous stabilizer for use in vein puncture including a handle portion and a rigid spatula-like blade, said blade being provided at its end with a deep notch open 100 at the end remote from the handle whereby when said blade is pressed over a distended vein, the vein will be closed at one end by the blade and will balloon through said notch. 105

3. A vein stabilizer of the class described including a handle having a blade attached thereto, said blade having its end remote from the handle cut off at an angle and provided with a notch at an angle to the 110 axis of said blade.

4. A vein stabilizer of the class described including a handle, a blade secured thereto at an angle, said blade having its distal end cut off at an angle to its axis and provided 115 with a relatively long notch with its major axis at an angle to said blade.

5. A vein stabilizer of the class described including a substantially flat handle, a flat blade extending therefrom at an angle substantially thirty degrees from the plane of the blade, said blade and handle having a common axial plane, a distal edge on said blade at an angle of substantially thirty degrees to the axis of the blade, said blade being provided with a notch having its major axis normal to said distal edge. 125

6. A vein stabilizer of the class described including a substantially flat handle, a flat blade extending therefrom at an angle of 130

- substantially thirty degrees from the plane of the blade, said blade and handle having a common axial plane, a distal edge on said blade at an angle of substantially thirty degrees to the axis of the blade, said blade being provided with a parallel sided notch having its major axis normal to said distal edge.
7. A vein stabilizer of the class described including a substantially flat handle, a flat blade extending therefrom at an angle of substantially thirty degrees from the plane of the blade, said blade and handle having a common axial plane, a distal edge on said blade at an angle of substantially thirty degrees to the axis of the blade, said blade being provided with a relatively deep, parallel sided and rounded bottom notch having its major axis normal to said distal edge.
- 10
- 15

lel sided notch having its major axis normal to said distal edge.

8. A vein stabilizer of the class described including a substantially flat handle, a flat blade extending therefrom at an angle of substantially thirty degrees from the plane of the blade, said blade and handle having a common axial plane, a distal edge on said blade at an angle of substantially thirty degrees to the axis of the blade, said blade being provided with a relatively deep, parallel sided and rounded bottom notch having its major axis normal to said distal edge.

In testimony whereof I hereunto affix my signature.

JOHN C. SILLIMAN.
